UNITED STATES PATENT OFFICE

LEE DELL S. KLOTZ, OF MALVERN, OHIO, ASSIGNOR TO THE WHITACRE-GREER FIRE-PROOFING COMPANY, OF WAYNESBURG, OHIO, A CORPORATION OF OHIO

KILN BOTTOM

Application filed January 8, 1927. Serial No. 159,883.

This invention relates to kilns for burning brick, tile and other clay products, and more particularly to down draft kilns.

The common type of down draft kilns now 5 in common use comprises a plurality of fire boxes located at spaced intervals around the wall, and provided with bag walls extending upward for a certain distance within the kiln, the floor of the kiln being perforate and supported upon spaced checkerwork walls provided with a flue communicating with the stack.

The objects of the present improvement are 15 to change the bottom construction of the kiln in order to increase the efficiency of the kiln and produce a better draft downward through the perforate floor to the flue, and to facilitate cleaning of the kiln bottom.

The above and other objects may be attained by increasing the depth of the kiln 20 below the floor and providing a downwardly and inwardly inclined wall surrounding the kiln bottom, spaced transverse walls extending across the kiln bottom to support the perforate floor, said transverse walls being provided with aligned openings, forming a flue 25 through the walls, communicating with the cross flues formed by the spaces between the transverse walls, a communication being provided between the outer end of this flue and the stack.

An embodiment of the invention is illustrated in the accompanying drawing, in which

35 Figure 1 is a plan sectional view through the improved kiln taken substantially on the line 1—1, Fig. 2, a portion of the perforate floor being broken away to show the transverse supporting walls; and

40 Fig. 2, a vertical sectional view taken substantially on the line 2—2, Fig. 1.

Similar numerals refer to similar parts throughout the drawing.

The drawing illustrates the invention as 45 applied to a down draft kiln which may include the circular side wall 1, the crown 2, a series of fire boxes 3, located around the side wall and each provided with a bag wall 4, spaced within the side wall and terminating 50 at a distance above the perforate floor 5, all

of which parts may be of usual and well known construction.

The downwardly and inwardly inclined walls 6 are located beneath the floor level and extend from the outer side wall 1 to the bottom level 7 which may be greater than the depth generally provided for kiln bottoms in standard practice. 55

A plurality of spaced transverse walls 8 extend across the kiln bottom, between the 60 downwardly inclined lower walls 6, supporting the perforate floor 5.

Each of these transverse walls is provided in its lower portion, substantially at its longitudinal center, with an opening 9 preferably in the shape of an arch. These openings, being in alignment, form a flue extending from front to rear of the kiln bottom and adapted to communicate at the forward end with a flue or tunnel 10 which may be connected to the stack. The downwardly and inwardly inclined walls 6 terminate at their lower ends at points spaced laterally from the aligned openings 9 in the spaced transverse walls 8. 75

The spaces between the transverse walls 8, as illustrated at 11, form transverse flues unrestricted throughout the length and breadth of the walls 8, all of which connect with the central exit flue formed by the arch openings 9, and as the walls 6 are inclined downward and inward, toward this central flue, there is a tendency for the products of combustion to follow the lines indicated by the arrows in Fig. 2, passing upward 80 from the fire boxes, over the bag walls 4 and then downward through the perforate floor 5 and between the transverse walls 8 to the central flue formed by the arch openings 9. 85

The inclined bottom construction crowds 90 the cold air toward the flue openings 9, permitting the hotter air to ascend toward or through the perforate floor, thus increasing the draft.

This construction also facilitates the cleaning out of the kiln bottom as all waste material will be carried down the inclined walls toward the flue openings, and a man may crawl through these flue openings and easily remove such waste material. 95 100

I claim:

A down draft kiln provided with perforate floor, downwardly and inwardly inclined side walls beneath the floor, spaced walls beneath the floor and abutting the side walls
5 forming transverse flues between the walls unrestricted throughout the length and breadth of the walls, said spaced walls having aligned openings in their lower portions forming an exit flue freely communicating with the transverse flues, said downwardly and inwardly inclined walls terminating at their lower ends at points spaced laterally from the aligned openings in the spaced walls, and an outlet communicating with said exit flue.

15 In testimony that I claim the above, I have hereunto subscribed my name.

LEE DELL S. KLOTZ.
